UNITED STATES PATENT OFFICE

HENRY J. SCHLACKS, OF CHICAGO, ILLINOIS

WINDOW CONSTRUCTION

Application filed November 2, 1928. Serial No. 316,857.

My invention relates in general to windows. It relates more in particular to an improvement in the type of inset window shown in my copending application Serial No. 187,569, filed on April 29, 1927.

One of the principal objects of the present invention is to improve the window construction of this copending application.

Another object is to produce a window of this general type having greater strength than prior windows of this class while still maintaining the relatively narrow frame and sash which is of advantage in admitting a greater amount of light for the size of the window opening.

Another object is to reinforce the inset window along the center thereof.

Another object is the provision of an improved latching mechanism.

Another object is to improve the frame structure in which the inset window is hinged.

Another object is to improve the hinge structure.

Another object is to provide a fastening mechanism for holding the inset window in a partially opened position.

Another object is to provide a window of this type which may be formed up entirely of sheet metal.

Another object is to provide an internal base for a narrow section of sash so that the wall of the sash may be formed of relatively thin cross section.

Other objects and features of the invention will be apparent from a consideration of the detailed description taken with the accompanying drawings, wherein

Fig. 1 is an elevational view on the inside of a window showing one form of my inset window in position;

Fig. 2 is an enlarged fragmentary vertical sectional view taken along the line 2—2 of Fig. 1;

Fig. 3 is an enlarged fragmentary horizontal sectional view taken along the line 3—3 of Fig. 1;

Fig. 4 is a fragmentary plan view showing one form of the catch mechanism;

Fig. 5 is an enlarged view partially in sec-

tion showing the arrangement at the hinge corners;

Fig. 6 is a fragmentary perspective view showing the arrangement of the latching mechanism;

Fig. 7 is a fragmentary perspective view of one form of mounting;

Fig. 8 is a front elevational view showing slightly different form which my invention may take;

Fig. 9 is a vertical sectional view taken along the line 9—9 of Fig. 8;

Fig. 10 is an enlarged fragmentary plan view;

Fig. 11 is an irregular horizontal plan sectional view taken along the line 11—11 of Fig. 8;

Fig. 12 is a fragmentary sectional view showing the corner construction of the casement;

Fig. 13 is a fragmentary perspective view showing the latching mechanism, and

Fig. 14 is a fragmentary sectional view showing modified arrangement of the casement brace.

The window of my present invention is in many respects the same as that shown in the copending application referred to, in that the outer frame is adapted to be secured within a large window pane and has a vertically pivoted sash adapted to be opened to permit access to the outside portions of the window without raising the same. The inset frame is formed at the top and bottom so as to fit into the main window sash, and has channels on the sides thereof into which the glass panes of the large window are glazed. The pane of the inset window is clamped all around the edge thereof by the inset window sash, the usual glazer's cement also being employed, and the sash being pivoted to the inset frame so as to swing through a full 180 degree arc and lie against the inside face of the main window.

I may form my window of various materials depending upon the particular results desired, and the conditions encountered; but in general I prefer to employ for one type either aluminum or a light aluminum alloy, and for another type I secure the best results

by the use of steel. In the drawings Figs. 1 to 7 inclusive show a design which I prefer to make use of when the material employed is aluminum or a light aluminum alloy; while Figs. 8 to 13 inclusive show a design making use of formed sheet steel. These two designs have many features in common and while best suited for the materials for which they are designed, may without difficulty be produced from other materials. Where therefore in the following description reference is made to the materials from which a window is produced, these materials need not necessarily be used, the scope of the invention being designated by the claims.

Referring now to the first form of the invention the inset window is adapted to be used with any species of large window, but it is shown with a window of standard double hung check rail type, the sash of the main window comprising a check rail 10, uprights 11 and 12 and bottom rail 13. The usual large pane of glass 14 is held in the sash of the main window but has a center portion thereof removed for receiving the inset window frame. The inset window is of the casement type and is hinged to the inset window frame and swings inwardly in a manner and for the purpose described.

The outer frame comprises an upper frame member 16, lower frame member 17 and side members 18-18. The top, bottom and side members are all differently formed but each is so arranged that the casement window may be fitted snugly thereagainst when the inset casement is closed.

The top frame member comprises a main horizontal web 16a thickened at 16b to form a better engagement with the casement, and is provided with a downwardly projecting flange 16c against which the top of the casement frame is held when closed. An upwardly extending flange 16d is fitted into the usual groove in the check rail and a screw or nail 19 extending through suitably provided apertures in the web 16a facilitates holding the upper frame member in position. The flange 16d is narrower than the slot or groove in the check rail, being about the same thickness as the window pane with which it is in alignment. The usual putty or cement 21 is employed in the groove and may be placed therein at the same time that the panes are glazed in the main window.

The bottom frame member is of general U shape with a bottom horizontal portion 17a and upstanding sides 17b and 17c, the side 17c being on the outside and serving as a stop for the casement and against which the casement is held in firm contact when in closed position. A thickened bevel flange 17d projects inwardly from the upright portion 17b and serves to engage the bottom of the casement. The bevel or slanting character of this flange serves to overcome any pos-

sible sagging of the casement by raising the casement upon the slanted surface as it is closed. The bottom frame member is wide enough at its lowest part so as to cover the entire putty space, attachment to the bottom rail being secured by nails or screws 22 driven through suitably provided holes in the bottom frame member and imbedded in the wood of the bottom rail. The usual weep holes 23 are formed to tap the well-like opening in the bottom frame member in order to drain any liquid such as condensate which may become lodged therein.

The side or vertical frame members are the same on each side with the exception of course that their positions are reversed. The cross sectional shape of these side members is shown in Figs. 3, 4 and 6. The members comprise a main web 18a, thickened at 18b, with outwardly extending flanges 18c and 18d giving rise to a channel therebetween, and an outside inwardly projecting flange 18e against which the inset casement bears when in closed position. The channel between the flanges 18c and 18d is to accommodate the glass pane of the larger window, this pane extending thereinto and held against the larger of the two flanges, cement 24 being employed to hold the glass in position.

Any suitable means may be resorted to for holding the four frame members together. I have obtained results most satisfactory to me, by mitering the corners and welding them together. This makes a substantially uni-piece frame and results in a more satisfactory job for most purposes.

The casement or sash is formed of four sides, namely the top 26, bottom 27 and two uprights 28-28 mitered and held together at the corners, suitably glazed and hinged to the inset frame. Each one of these members has the same cross sectional shape, and in order to make clear the arrangement and purpose thereof, reference will be made to the upper member 26 only. This member is of general U shape having a main web 26a with the portions 26b and 26c forming the sides of the U, and right angular flange projections 26d and 26e from the side U portions. The U shape character of the member gives rise to a relatively large channel, and the flange projection 26d projecting over the channel results in the production of a closed channel area 26f which is so arranged that the glass pane 29 cannot be extended thereinto. When the glass pane 29 is in place it lies against the edge of the flange 26d and so closes off the area 26f as to completely separate it from the other portions of the channel. Cement 31 is employed to fill the balance of the channel after the pane 29 is in place.

Where an unusual strain is applied to any of the frame members I may modify the thickness of the walls to secure greater

strength, or as I prefer to do in most instances I may employ a reinforcing insert 30 which will positively prevent all torsional strain on the sash frame, as well as considerably augmenting its strength in bearing ordinary bending stress. I have found that the greatest strain is in the member to which the hinges are secured, and I accordingly show the insert employed within this member. It is shown having a formed shape to facilitate anchoring it in place but it may take any shape desired which will have a satisfactory reinforcing effect. The shape of insert shown (vide Fig. 3) has the advantage of permitting the glass to be extended farther into the sash frame.

In securing the four sides of the casement or sash together, the corners are mitered and two of the corners connected by welding so that three pieces are connected together to make a three sided figure. The third side which is the one bearing the hinges, is secured in place in a special manner which so relates to the arrangement of the hinges that it will be described in connection therewith.

The hinges comprise two hinge plates 32 and 33 with the usual form of hinge pin 34 securing them together. The hinge plate 32 is secured to the side 28 of the casement by means of rivets 36—36, one short rivet extending through the web 28a and flange 28d, as well as through an angle insert 37 which is square in cross section and fits into the closed channel area 28f (Fig. 5). Then to secure in position the side 28 bearing the hinges, the opposite leg of the angular insert 37 is extended into the closed area 26f of the top casement member and secured therein by machine screws 38—38 extending through the web 26a. These machine screws are countersunk so as to interfere in no way whatsoever with the operation of the window, and at the same time the heads thereof are normally concealed from view. A rivet 36a is also secured through the member 28 and the angular insert 37, without having any connection whatsoever with the hinge.

In hanging the casement or sash of the inset window, the hinge plates 33 are secured by means of machine screws 39—39 to the uprights 18. Preparatory to securing the hinges in place, however, a slot is cut in the thickened portion 18b of the web as wide as the hinge plate but double the thickness thereof, so that this slot is adapted to hold both hinge plates when the window is closed and accordingly the hinge plate 32 is secured directly onto the sash member without preparing it in any way with the exception of course of drilling the usual rivet holes therein.

In securing the hinges in place, the plates may be secured with substantially their whole area in contact with the members to which they are secured as shown in the present case

or the hinge may project considerably beyond the two upright members so that the hinge pin is, say a half an inch, an inch or even more away from the upright members. This is a more or less ordinary modification in the use of hinges but inasmuch as I have shown the prior arrangement, I wish to bring out the fact that the hinges may be arranged so that if there is any object to be cleared when the inset casement lies back in extreme open position, the necessary changes in the hinges may be made.

While I may employ many different kinds of latching mechanisms with my invention, still all of the conventional arrangements with which I am familiar are disadvantageous in some respect or other, accordingly, I have provided a novel arrangement making use of the peculiar arrangement of the sash and frame and functioning very satisfactorily in this particular position.

A latching rod 41 (Figs. 3 and 6) is provided to fit snugly into the closed area 28f and having right angular projections 41a at both the top and bottom thereof extending through elongated slots 42 in the web 28a. The portion 28b of the upright casement member has a slot 43 through which a connection is made to a plate 44 by means of screws 46 extending through the plate and into the latching bar. A handle 47 is also provided on the plate 44, this handle 47 being secured thereto by a screw 48 threaded through the hollow interior of the handle and having a relatively large head which bears against the latching rod 41 so that when the screws 46 are pulled up tightly, the cover plate 44 is held securely to the latching rod 41 but at the same time such plate has no tendency to bind against the face of the flange. An angular insert 49 of sheet metal or similar thin material is provided to avoid the possibility of the cement 31 coming in contact with the latching rod and cramping its action. In order to form an engagement with the projecting ends 41a of the latching rod, cam slots 51 are provided in the thickened portion 18b of the web, so that as the window is closed, the projections 41a extend into the cam slot directly, and downward pressure of the handle 47 draws the latching rod 41 downwardly and causes the projections 41a to ride along the cam slot and force the entire casement or sash outwardly, so that the portions, 26c, 27c and 28c bear against the stop flanges on the inset window frame.

The inset window of my invention has very narrow frame and sash members so that only a limited amount of light is cut out thereby; nevertheless, exceptional strength is obtained by the particular arrangement employed, which is sufficient for all ordinary installations. However, if an exceptional long inset window is employed as indicated,

I may provide a strengthening muntin across the center of the casement, or as a matter of fact such a muntin may be employed for decorative purposes only and constituting part of a general decorative scheme. Independent of what the muntin is, the arrangement illustrated in Figs. 1, 2 and 7 may be employed. In this arrangement, the muntin comprises a pair of parallel webs 53 and 54, one slightly wider than the other, and connected at their centers with a continuous intermediate web 56 so that a member of substantially I-shape cross section is obtained. To prepare the muntin for mounting in position, portions of the webs 53 and 54 are cut off the end thereof so as to result in end projections 56a which extend into the channels in the side casement members 28, the muntin being secured in position by machine screws 20 through the web of the members 28 and extending into threaded screw holes in the end projections 56a. The glass pane is glazed in the channels between the flanges 53 and 54 as shown in Fig. 2.

An inset window of this type is of advantage to permit washing the window without going to the outside thereof and also to facilitate ventilating. When used for cleaning or repair purposes, the casement is swung through a full 180 degree arc so as to lie flat against the inside of the main window. When employed as a ventilator, however, it is desirable at times to have the window only partially open and for this reason I provide 35 a holding mechanism so that the window may be secured in various partly open positions.

One form of fastener with which I have obtained good results comprises a single rod 57, of spring material having an upturned projection 58 extending through the check rail and held in place by a nut 59, and a shorter downward projection 61 at the other end of the rod adapted to fit into any one of a plurality of apertures 62 and the web 26a of 45 the top casement window. The apertures 62 are connected by a groove 63 which is of advantage in facilitating insertion into the apertures. As illustrated in Fig. 2, the portion of the rod 58 is secured in the check rail 50 at a slight angle so that when the rod extends out away from the check rail in the position in which it engages in the apertures 62, it extends partly downwardly, thereby serving to hold the downward projection 61 firmly 55 in position. When the window is closed, however, and the rod 57 swung back against the check rail, it is drawn up to a full horizontal position again and allows the casement window to pass freely under it.

In manufacturing and using the window, the following procedure is observed: First of course all of the necessary strips are cut the proper length and mitered for securing them together at the corners. The frame 65 members are provided with the cam slots

51 on one side and the slots on the other side for receiving the hinges. The four sides of the frame are then welded together at the corners and this completes the manufacture of the frame.

In the manufacture of the casement or sash side bearing the latching rod, it is first provided with the slots 42 and the slot 43. The latching rod 41 is then slipped into the closed channel area 28f with the projections 41a extending through the slots 42. The plate 44 with the handle 47 secured to it, is then placed over the slot 43 and the screws 46 employed to fasten the plate to the rod, suitable screw holes having been provided previously therein. The other side member of the casement is then prepared, the angular inserts 37 being secured in the area 28f of this side by the rivets 36a. The hinge plate 32 has previously been secured in position by a smaller rivet or screw and the long rivets 36 are then placed in position extending through two portions of the side member and through the hinge plate. The top and bottom and the side member containing the latching rod are then welded together making a three sided figure, the glass pane slid sideways into its channel, and the side bearing the hinges then secured in position. This is done by simply extending the free legs of the angular inserts 37 into the closed channel area of the top and bottom members and screws 38 then employed to complete the assembly. The usual glazer's cement is of course used to complete the job.

When assembling the complete inset window into a large window, the frame is glazed into the large window in the same way that the glass panes 14 are. As a matter of fact, I prefer to secure all of them in position at the same time. The inset casement may of course be secured in its frame before the frame is mounted in the window; but if not it is secured in position by the simple expedient of applying the screws 39.

The form of invention shown in Figs. 10 to 13 inclusive is particularly adapted to be produced from sheet metal, preferably sheet steel which is either in itself rust proof, or which is treated by a coating or the like to make it rust or weather proof. The principal purpose in connection with the manufacture of the window formed from sheet metal is to produce a stronger structure, with the frame all the narrower so as to offer less obstruction to the light, and probably most important of all to reduce the cost of manufacture. This and other objects are accomplished by the design of the members which I show in the drawings now under consideration.

In the description of the second form of the invention I shall as far as possible employ reference characters identical with those employed in connection with the first embodiment.

ment with the exception of the prefixing of a digit 1. For example where a reference character 10 is employed in the first form the member in the second form of the invention corresponding with the member 10 in the first form of the invention will bear the reference character 110. This is for the convenience of those skilled in the art in arriving at a clearer understanding of the invention, and is not intended to limit or introduce any matter in derogation of the scope of any of the features.

The inset window of this form is also adapted for use with a standard window of the double hung check rail type, the sash of the main window comprising a check rail 110, uprights 111 and 112 and a bottom rail 113, the usual large pane of glass 114 being supported by these members.

20 The outer frame comprises an upper frame member 116, lower frame member 117 and side frame members 118—118. In this form of the invention the top, bottom and side members are all of the same cross section, a form 25 being utilized which will not only receive the large window when these members are used as side members, but with substantially equal facility may be secured to the check rail and bottom rail of the main window.

30 For this reason as far as an understanding of the shape of this member is concerned a description of the side members will suffice.

The side and vertical frame members of the inset frame are mounted in identical positions 25 with the exception that they are reversed. The members comprise a main web 118a taken at 118b with outwardly extending flanges 118c and 118d giving rise to a channel therebetween with an outside inwardly 40 projecting flange 118e against which the inset casement bears when in cross position. This member is formed entirely of sheet steel, the outer projection 118c being formed by bending the material from the web out- 45 wardly and then doubling it back upon itself to form a wide outer flange, and a relatively thin inside or stop flange. The thickening at 118b is also produced by employing a double thickness, but in this respect the

50 shape is somewhat different than in the aluminum form. The thickening is on the outside instead of on the inside of the flange, and a separate inside projection 118f is formed by bending the web at right angles toward 55 the inside, and then back on itself to produce the inside flange and also an inside channel serving a number of useful purposes some of which have been pointed out, and others of which appear obvious. The material is then 60 bent around the corner to extend partly the width of the web and then at right angles again away from the web to form the outwardly extending flange 118b.

As the drawing shows the frame has the 65 same cross section all the way around. In

forming the frame the four members are cut to proper size and mitered at the corners, after which they are welded together and secured in any other suitable way so as to make a substantially single piece frame. The results secured by welding are the most satisfactory from all standpoints. In securing the frame in the large window the flange 118d on the upper frame member is fitted into the usual groove in the check rail and a screw or rail 119 extends through suitably provided apertures in the web, glazer's cement or putty 121 being employed to secure a weather proof joint. The bottom member is brought into position as shown in Fig. 9, 80 and held in position by suitable rails or screws 122. A liberal quantity of cement or putty is employed to fill in the space below the web 118, and the usual weep holes 123 are provided.

In securing the side frame members they are simply glazed with the large window, the glass being extended into the outside channels and secured by the usual glazer's cement 85 124.

The sash or casement is formed of four sides, namely, a top 126, bottom 127 and two uprights 128—128 mitered and held together in the corners suitably glazed and hinged to the inset frame. Each one of these members always has the same cross-sectional shape, this shape being substantially the same shape as with the aluminum form. This member is of general U shape having a main web 126a with portions 126b and 126c forming the 100 sides of the U and right angular flange projections 126d and 126e from the side view portions. This gives rise to a relatively large channel, with the flange projections 126d projecting over the channel and results in the production of a closed channel area 126f which is so arranged that the glass pane 129 cannot be extended thereinto. When the glass pane 129 is in place it fits 105 against flange 126d and closes off the area 126f entirely. Cement 131 is employed to glaze the pane in place and obtain a tight weather proof joint.

The sash or casement frame is made of relatively thin material, in fact I prefer to 115 employ as thin a material as possible consistent with obtaining the requisite strength; material which is thin enough to possess in itself insufficient strength may be employed with very good results by utilizing a reinforcing strip 130, this strip extending diagonally across the inside of the U channel of the frame and thus increasing tremendously the torsional strength and bending resistance of the sash frame. I prefer to form 120 this bracing strip with separate continuous longitudinal portions 130a and 130b, the portion 130a lying along the portion 126b in the upper sash member, and the portion 130b lying along the web 126a in the same loca- 125 130

- tion. This reinforcing strip may be simply slid loosely into position, or to increase its strengthening effect it may be secured in place. This is done preferably by spot welding the portions 130 a and 126 b together, and the portions 130 b and 126 a together. Two or three spot welds are sufficient, but more may be employed depending upon the length of the members secured.
- 10 Besides the advantage of being able to secure the reinforcing or strengthening strip in place when this form is employed, it is also found that slightly greater space is provided for the glass than when a straight strip 130' is used as shown in the modified form of Fig. 14. This modified form, however, may possess certain advantages which will make it advisable to use it with certain types of installation.
- 15 20 The hinge arrangement in this form I prefer to simplify by spot welding hinge plates 132 and 133 to the outside surfaces of the casement frame and inset frame respectively, any usual form of hinge pane 134 being provided.
- 25 In this way the hinges form a substantially permanent part of the frame structure, but the hinge pane may be removed readily without separating the casement for repair or the like.
- 30 35 In producing the finished structure of the casement frame the members 126, 127 and 128 are cut and mitered at the corners, being secured together by welding and by the insertion of angle inserts 137 which in the present form I prefer to make wide enough to extend clear across the inside channel as the drawings illustrate. To do this, however, the reinforcing strip 130 is held at the end of the angle insert, this arrangement being shown
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955
- The latching mechanism employed is substantially the same, a latching rod 141 being operable through slots 142 in the web. The portion 128 b of the casement is slotted to permit a connection from a handle 147 to the rod 141 so that said rod may be reciprocable vertically to latch and unlatch the window. For the purpose of providing an engagement between the projecting ends of the rod

141 and the inset window frame, the portion 118 f has a section 150 partly struck therefrom and extended inwardly in the manner shown in Fig. 13 to form a slot into which the end 141 a extends. A cam-piece 151 is secured to the inside of the frame member just below the slot, so that as the latching lever is pushed downwardly the camming action of the end 141 a against the piece 151 will force the casement tightly against the stop flanges and effectually prevent any rattling either of the window or of the latching mechanism. The inturned portion 150 also functions to assist in opening the window, as when the end 141 a strikes against this inturned portion a camming action takes place in the opposite direction and tends to pull the casement outwardly.

In this form I show also a slightly different fastening rod 157, but it is arranged to accomplish substantially the same result as the previously described fastener. It is formed of spring material and has a bifurcated or forked end 161 which is adapted to engage over the top of the casement. The member 157 being formed of spring material and having its upward projection 158 secured in the check rail at an angle, the bifurcated end will extend on both sides of the casement with a spring tension. The angle of the pivot 158 causes a tighter engagement of the casement the farther open the window is, so that the wind blowing against the window cannot cause the fastener to loosen. This angle also permits the fastening rod to be swung up out of position as shown in Fig. 8 so that the casement may be entirely closed.

In assembling the window form as illustrated in Figs. 8 to 13 substantially the same procedure is observed as described in connection with the aluminum frame window. In actual use I have obtained good results with both of these forms, but conditions may suggest the combination of certain of the features in the two forms, or slight changes therein. The muntin for example may be employed with the sheet steel type of frame and any of the other features may also be interchanged. As already pointed out the selection of materials is in general illustrative, but there are certain features in connection with the use of sheet steel which I consider novel and which require considerable thought and development before this material could be applied to the use of this type of window. For these reasons I do not wish to restrict myself to any of the features, materials or the like above set out, the invention being limited only by the scope of the appended claims.

What I claim as new and desire to secure by United States Letters Patent is:

1. In an inset casement window, a frame member comprising a web having a casement stop and a flange on the outside thereof,

said web being thickened on the inside of the window to a point overlapping said flange whereby a wide bearing surface is provided for the casement window, and a channel results between said thickened portion and said casement stop.

2. In an inset casement window, a frame with top and bottom members for fitting into a large window frame, and side members for receiving the edges of glass panes, the side frame members each comprising a web with a pair of outside flanges between which the large window pane extends, and a casement stop in the form of a flange projecting in the opposite direction from said first mentioned flanges, the web being thicker on the inside to a point including the inside one of said pane receiving flanges.

3. In an inset casement window, a casement having frame members of general channel cross section for receiving an inset glass pane, and a muntin extending across the casement, said muntin being of general I cross-section consisting of parallel members connected intermediate their ends by a web placed at right angles thereto with top and bottom channels for receiving separate sections of inset glass, projections on the end formed from said web for extending into the channel casement, connection between the muntin and casement being made by screws extending through the casement into said end projection on the muntin.

4. In an inset casement window having a frame, a casement hinged to said frame and having its frame members of general U-shape cross section with an outside web and inwardly projecting legs of the U, and a right angular projection on one of the legs of the U resulting in a closed area in said channel, a latching rod reciprocable in the closed area and having its ends extending at right angles through slots in said web and adapted to cooperate with cam slots in the frame for closing the casement tightly, a slot being formed in the leg of said U and a handle extending through the slot and engaging the rod for reciprocating said latching rod to latch or unlatch the window.

5. In an inset casement window having a frame, a casement hinged to said frame and having its frame members of general U-shape cross section with an outside web and inwardly projecting legs of the U, and a right angular projection on one of the legs of the U resulting in a closed area in said channel, a latching rod reciprocable in the closed area and having its ends extending at right angles through slots in said web and adapted to cooperate with cam slots in the frame for closing the casement tightly, a slot being formed in the leg of said U, a plate covering said slot and having screws engaging into the latch rod, and a handle secured to the plate and having an inside projection engaging against

the latching rod to limit the tightening of said screws and so preventing binding of the plate over said slot.

6. In an inset casement window a casement frame of general channel cross-section and having a longitudinally extending diagonally positioned bracing strip secured therein for reinforcing the frame.

7. In an inset casement window a casement having frame members of general channel cross-section with a longitudinally extending diagonally positioned bracing strip secured therein and having its edges bent from the main plane thereof and spot welded to the casement frame.

8. In an inset casement window, casement frame members of general channel cross-section with an inwardly extending flange on one of the legs of the channel forming an interior corner, and a bracing strip extending across diagonally from this interior corner to one of the corners in the channel.

9. In an inset casement window, a frame with top and bottom members for fitting into a large window frame, and side members for receiving the edges of glass panes, the lower frame member being of general U-shape and adapted to set into the usual putty space on the bottom rail, the outside leg of the U being higher than the inside leg and serving as a stop for the casement.

10. In an inset casement window, a welded frame formed of four frame members mitered at the corners, the top frame member and bottom frame member provided with outside projections for securing the same to a large window frame, and the side members having a pair of flanges resulting in a channel for receiving the glass pane of said large window, the material of the frame members being relatively thick on the inside and to a point including said outside projection and one of said flanges.

11. In an inset casement window, a frame with top and bottom members for fitting into a large window frame, and side members for receiving the edges of glass panes, the lower frame member being of general U-shape and adapted to set into the usual putty space on the bottom rail, the outside leg of the U being higher, and serving as a stop for the casement, and the inner leg of the U having an inwardly extending projection against which the lower portion of the casement rests.

12. In an inset casement window, a frame with top and bottom members for fitting into a large window frame, and side members for receiving the edges of glass panes, the lower frame member being of general U-shape and adapted to set into the usual putty space on the bottom rail, the outside leg of the U being higher than the inside leg and serving as a stop for the casement, and the inner leg of the U having an inwardly extending projection against which the lower portion of the

casement rests, said inwardly extending projection being bevelled to compensate for any slackness in the casement, the casement riding upon the bevel section as it is closed.

5 13. In an inset casement window, a frame with top and bottom members for fitting into a large window frame, side members for receiving the edges of glass panes, said upper member comprising a web with an upper projection for engaging in a groove in a check rail, said web being thicker on the inside to a point overlapping said upper projection.

10 14. In an inset casement window, a frame with top and bottom members for fitting into a large window frame, side members for receiving the edges of glass panes, said upper member comprising a web with an upper projection for engaging in a groove in a check rail, said web being thicker on the inside to a point overlapping said upper projection, and said upper frame member also including a depending casement stop, a channel being provided between the thick portion of the web and said casement stop.

20 15. In an inset casement window, a frame, a casement comprising four side members, two of which are mitered and welded at the corners to form a three sided figure, angle inserts fixed to the remaining side member, 25 hinges secured to the inserts and remaining side member and to said frame and means for removably connecting the three legs of the inserts to the three sided figure to complete the assembly of the casement.

30 16. In an inset casement window a frame member formed of folded sheet metal and having a web with a pair of outside flanges and a pair of inside flanges, one inside flange and one outside flange being formed by folding the material at right angles and then extending it back on itself, and in each instance the opposite flange comprising a single thickness of such material resulting from folding the material back on itself in the production 35 of the double thickness flange.

40 17. In an inset casement window a frame formed of folded sheet metal and having a web, with the material at one side of the web folded at right angles and then doubled back on itself and extending in a direct line so as to produce a double thickness outer and a relatively long single thickness inwardly extending stop flange, and the other side of the web having the material thereof folded 45 at right angles toward the inside and then back on itself to form a double thickness inside flange, and the material being doubled under the web to form a double thickness portion of web, and then extending downwardly at right angles to form a single thickness outside web, an outside channel for receiving a glass window frame being thereby formed, and the single thickness outside flange extending a distance greater than the 50 double outside flange to permit said single

thickness outside flange to extend into suitably provided spaces in a check rail and bottom rail of a large window, so that said frame may be formed of the same cross-section throughout.

55 18. In an inset casement window an inset frame and a casement frame both formed of folded sheet metal, the inset frame having an outer channel for receiving glass panes on the side thereof and an extending flange for inserting in a check rail and bottom rail of a window, with a stop flange against which the casement frame extends, and the casement frame being of general channel cross-section and having an outwardly extending flange jutting against and extending beyond the stop flange of the inset frame to produce a weather proof connection between the two frames.

60 In witness whereof, I hereunto subscribe my name this 17th day of September, 1928.

HENRY J. SCHLACKS.
